UNITED STATES PATENT OFFICE.

FREDERICK HENRY BERGMAN, OF NEWTON, IOWA.

WASHING-MACHINE.

1,287,621.

Specification of Letters Patent. Patented Dec. 17, 1918.

Application filed May 6, 1915. Serial No. 26,218.

To all whom it may concern:

Be it known that I, FREDERICK HENRY BERGMAN, a citizen of the United States, residing at Newton, in the county of Jasper and State of Iowa, have invented certain new and useful Improvements in Washing-Machines, of which the following is the specification.

This invention relates to washing machines, and more particularly to mechanisms associated therewith whereby a current of water and air is caused to pass continuously in one direction through the clothes to be washed.

It is an object of my invention to provide a washing machine of simple and economical construction in which the washing operation is assisted by currents caused to be set up in the clothes to be washed.

It is another object of my invention to provide a washing machine in which the clothes are at the same time pounded and influenced by currents set up in the water in which they are submerged.

Other objects and advantages of the invention will appear as the description to follow proceeds.

In the drawings:

Figure 1 is an elevation partly in section of a washing machine according to my invention.

Fig. 2 is a plan view of the same.

Fig. 3 is an enlarged detailed sectional view of the pounder operating mechanism.

Fig. 4 is a plan view of the same partly in section.

Fig. 5 is a bottom view of the pounder head.

Fig. 6 is a sectional view of the same on the line 6—6 of Fig. 1.

In the drawings: 1 represents a washing machine tub supported on legs such as 2, with a lid 3, as is customary, and a stationary partial cover 4 to which the lid is hinged.

Mounted upon the stationary part 4 is a support or plate 5 having upstanding ears 6. Mounted upon the lid 3 is a plate or support 7 having upstanding ears 8 and 8' which are pivotally connected to the ears 6 above described, so that the lid can be swung to open position. The ear 8' is provided with an extending bearing 9 in which is mounted a shaft 10 carrying at its outer end the gear 11 which meshes with the pinion 12 revolving upon a shaft 13 carried by a bracket secured to the side of the tub. The pinion 12

is cast integral with the fly-wheel 14 carrying a flange 15 to provide a belt pulley. The fly-wheel 14 is grooved, as indicated at 16, for a belt rope drive. Mounted upon the lid 3 of the tub is a support or plate 17 provided with upstanding brackets 18. The support 17 has an aperture therethrough over which is a chamber formed by the cap piece 19 bolted to the plate 17 and the tub by 60 ears 20.

Mounted in bearings in the brackets 18 is a bell crank comprising an arm 21 and an arm 22 in which is removably mounted the handle 23 by means of the flange 24. Connected to 70 the arm 22 is a link 25 at its other end pivotally connected to a crank pin 26 upon the disk 27 rigid with the shaft 10, which is supported at this point by the bearing 28 integral with the plate 17. In the chamber 19 is a crown ratchet 29 having a square orifice therethrough 30, through which projects the squared shaft 31 carrying at its lower end the pounder head 33, the shaft 31 at its opposite end being pivotally connected by a ball 80 and socket joint 32 to the link 25, which in turn is pivotally connected to the bell crank arm 21. Mounted upon the arm 22 of the bell crank is a pawl 34 which is bent outwardly, as shown at 35, and at its forward end passes 85 through a slot 36 in the cover 19, and engages with the crown ratchet 29. The spring 37 is fastened to the cover 19 and to the arm 22 to counterbalance the weight of the head 33.

Upon the lower end of the shaft 31 is mounted the pounder head which is of oblong form and conical in cross section and divided by a partition, such as 38, into two sections 39 and 40. At the top of each section is inserted a nipple such as 41 having an air orifice 42 communicating with the chamber 43 in which is seated a ball 44, the chamber being closed by the perforated screw 45.

In operation the machine when operated either by means of a belt applied to the fly-wheel, or a flat pulley thereon, or by means of the handle 23, will cause the bell crank 21—22 to rock upon its pivots operating the pawl 34 and at the same time vertically reciprocating the shaft 31. The result is that the oblong pounder head will be continuously rotated as well as violently moved up and down in the water and clothes. When the pounder head moves downwardly obviously a stream of air and water will be forced through the clothes and upwardly

through the ball valves and perforated nipples 45. When the head is raised the ball valve will be closed and by a vacuum action fresh water and air will be forced through the clothes in the same direction. This action, in addition to the rotating and pounding operation of the pounder head will very materially increase the efficacy of the machine. The oblong form of the pounder head is an important feature of my invention, inasmuch as it performs a more thorough action upon the clothes and causes a better rotation thereof in the tub.

When the machine is operated from the handle 23 the fly-wheel 14 acts as a power momentum device for storing up the power in the machine.

Having now described my invention:

I claim:

- 20 1. In apparatus of the class described, a tub, a lid thereon, a shaft having a pounder head thereon, a collar slidably but nonrotatably mounted with respect to said shaft, a rocking member to reciprocate said shaft and a connection from said rocking member to said collar to rotate said shaft as it reciprocates, and a momentum device to store up energy and connected with said rocking member by speed increasing gearing.
- 30 2. In apparatus of the class described, a support, a hinged member on said support, a bracket on said hinged member, a rocking shaft on said bracket, a crank on said shaft, a vertical reciprocable shaft rotatably connected to said crank, a second crank on said rocking member, means operated by said second crank to revolve said vertical reciprocable shaft, a third crank on said rocking member, means operated by said third crank to store up momentum, and means to operate said rocking member.
- 40 3. In apparatus of the class described, a support having a hinged member thereon, a vertical upright bracket on said support, a rocking member on said vertical upright bracket, arms connected with said rocking member, connections whereby one of said arms operates a vertical reciprocable shaft, another of said arms intermittently rotates said shaft, a third of said arms operates a power momentum device, and a fourth of said arms serves as means for manually operating the swinging member, substantially as described.
- 50 4. In apparatus of the class described, a support, a hinged member mounted thereon, a bracket mounted on said hinged member, a rocking member mounted on said bracket,

a reciprocating and oscillating shaft operated by said rocking member, a shaft mounted on said support in the hinge line of said hinged member, a crank on said second mentioned shaft, and a connection between said crank and said rocking member, a gear on said second mentioned shaft, and a rapidly rotatable member mounted on said support and adapted to be operated by said gear.

5. In a washing machine a support, a hinged member on said support, a bracket on said hinged member, a rocking member pivoted to said bracket, a vertical reciprocable shaft operated by said rocking member, a collar surrounding and slidably but non-rotatably engaging said shaft, ratchet teeth on the upper face of said collar, and a pawl pivotally connected with said rocking member and engaging said ratchet teeth whereby movement of the rocking member will both reciprocate and rotate said shaft.

6. In a washing machine a support, a hinged member thereon, a bracket on said hinged member, a bell crank pivotally mounted in said bracket, a vertical shaft, a link pivotally connected at one end with one arm of said bell crank and connected at its other end by means of a ball and socket joint to the end of said vertical shaft, a collar mounted on said hinged member and surrounding and slidably but non-rotatably engaging said shaft, and means operated by the other leg of said bell crank and engaging said collar to cause the collar and shaft to rotate as said shaft is reciprocated by said link and bell crank.

7. In a washing machine a support having a hinged member thereon, a bracket on said hinged member, a rocking member pivotally mounted on said bracket, a vertical reciprocable shaft operated by an arm from said rocking member, a pounder head on said shaft, a collar slidably but non-rotatably mounted with respect to said shaft, an arm from said rocking member to said collar to rotate said shaft as it reciprocates, a third arm on said rocking member, a momentum device to store up energy and connected to said third arm, and means to counteract the weight of the pounder head and tend to normally hold it in elevated position.

In witness whereof, I hereunto subscribe my name to this specification in the presence of two witnesses.

FREDERICK HENRY BERGMAN.
